APPARATUS FOR GENERATING HIGH FREQUENCY OSCILLATIONS

William Spencer Percival, Ealing, London, England, assignor to Electric & Musical Industries Limited, Hayes, England, a company of Great Britain

Application December 1, 1938, Serial No. 243,362
In Great Britain December 2, 1937

9 Claims. (Cl. 250—36)

This invention relates to apparatus for generating high frequency oscillations and is concerned more particularly with apparatus for generating higher frequencies than can be generated by the usual thermionic valve circuit arrangements owing, among other things, to the gird and plate capacities of the valves.

It has previously been proposed to employ cathode ray tube apparatus for the generation of very high frequencies and in such apparatus it has been proposed to employ a collecting electrode upon which the electron beam impinges after being subjected to deflection and interception by an apertured electrode. One of the main difficulties met with in arrangements of this description is to obtain either sufficient current to operate a low impedance collector electrode system or an electrode system having a sufficiently high impedance to operate on the small currents normally available.

The object of the present invention is to provide an extra high frequency oscillation generator of the nature referred to but having a collector electrode system which has a high impedance.

According to the present invention a method of generating high frequency oscillations comprises generating an electron beam and projecting said beam towards a target electrode which is resonant at the oscillation frequency to be generated and deflecting said beam over a surface which serves to intercept the beam intermittently before it impinges upon said target, and wherein in order to raise the impedance of said target its radiation resistance is reduced by the provision of a shielding member or by suitably shaping said target. The surface which serves to intercept the beam intermittently may be a member formed with apertures through which the beam passes successively due to deflection, before impinging upon the target, the frequency of the oscillations generated being determined by the number of apertures in the member and the speed of deflection from one aperture to the next. The target may constitute the extremity of the central core of a coaxial conductor or it may be an elongated member which is bent back upon itself so as to form a short resonant transmission line. Again auxiliary elements may be arranged in close proximity to the target in order that its radiation resistance may be low compared with that of a dipole aerial.

In order that the invention may be more

clearly understood and readily carried into effect, some alternative forms of high frequency generating apparatus will now be described by way of example with reference to Figures 1, 2 and 3 of the accompanying drawing.

Referring to Figure 1, parts of an electrode system of a cathode ray tube T are shown including a cathode 1, the electrons from which are formed into a beam 2 by an electron gun not shown in the drawing. The beam is deflected at a high speed in a circular path by two pairs of deflecting plates 3, 3 arranged at right angles. A sinusoidal voltage is applied to one pair of plates and another sinusoidal voltage having a phase displacement of 90° with respect to the first is applied to the other pair of plates. The deflected beam impinges upon a circular member 4 having apertures 5 formed near its periphery. The deflected beam passes through the apertures in turn and is focused by a coil C upon a target or collector electrode 6. The focussing arrangements ideally would be such that the beam is focussed in the apertures 5 and also at the target 6, but as this is difficult to achieve in practice, the voltages applied to the electrodes of the electron gun are such that the beam would be in the absence of the focussing coil C, have its focal point in the plane D—E shown in dotted lines, midway between the disc 4 and target 6, the loss from accurate focussing being insignificant. The electrode 6 thus receives charges at regular intervals, the frequency being equal to the frequency of rotation of the beam multiplied by the number of apertures in the member 4. For example, if the frequency of the rotation of the electron beam is 100 Mc./s and there are 50 apertures in the member 4, the oscillation frequency generated will be 5,000 Mc./s.

40 The target or collector electrode 6 may form part of a resonant circuit which may either be bent back on itself as shown in Figure 1 or otherwise rendered substantially nonradiating by being formed into shapes known to those skilled in the art. It may, of course, consist of more than one half wavelength. Auxiliary elements may be provided for the purpose of reducing the radiation of the target 6, the fundamental object always being to reduce the radiation resistance. The electron beam should impinge on the point in the target at which the impedance is highest, or if it is found that a sufficient impedance can be obtained, at a point at which the impedance is equal to the optimum

load resistance for the cathode ray tube considered as a valve.

Provision may be made to enable the field which focusses the electron beam onto the target 6 to be varied in such a manner that the point at which the beam impinges upon the target may be that which provides the optimum impedance. In Figure 1, for example, the point at which the beam impinges on the target may be selected between A and B.

In an alternative arrangement shown in Figure 2 the target or collector electrode 7 is shown arranged inside the outer sheath 8 of a transmission line or a continuation thereof, this outer sheath constituting the auxiliary element. The electrode 7 is coupled to the main inner conductor 9 by a transmission line transformer 10 or other convenient means. In this arrangement the end of the conductor which forms the target electrode 7 or is connected to that electrode, should be a point of high impedance for example, Z_1 and be coupled to the main portion of the transmission line of the impedance Z_0 by a suitable length, for example, a quarter of a wavelength of impedance Z_0 such that $Z_1^2 = Z_0 Z_1$.

An arrangement similar to Figure 2 is shown in Figure 3 but in this case the quarter wavelength conductor 10 is connected to the sheath 8 at a point 11, and is tapped at a suitable point by the main conductor 9.

In either of the arrangements shown in Figures 2 or 3 the main conductor may be connected directly with a suitable aerial for example, a dipole.

I claim:

1. Apparatus for generating high frequency oscillations comprising an evacuated envelope, a source of electrons and a target electrode mounted within said envelope, means for projecting a beam of said electrons towards said target electrode, an orificed member, means for deflecting said beam over a surface of said member which serves to intercept the beam intermittently, and means for causing certain of the electrons to strike a focal spot on said target electrode where its impedance is of an optimum value in relation to an external load resistance connected thereto, said target electrode and its mounting being further characterized in that they form a resonant circuit entirely within said envelope, said resonant circuit being tuned to the frequency of oscillations generated by the intermittent impacts of electrons on said target electrode, and constituting means for minimizing the dissipation of energy by radiation.

2. Apparatus for generating high frequency oscillations comprising a source of electrons, means for forming said electrons into a beam and for projecting said beam towards a target electrode which is resonant at the oscillation frequency to be generated and has relatively high impedance, and means for deflecting said beam over a surface which serves to intercept the beam intermittently before it strikes said target electrode, said target forming the extremity of the central core of a coaxial conductor system, said target electrode being of a high impedance Z_1 and coupled to the main portion of a transmission line of impedance Z_0 by a length of conductor of impedance Z_1 such that $Z_1^2 = Z_0 Z_1$.

3. Apparatus for generating high frequency oscillations comprising a source of electrons, means for forming said electrons into a beam and for projecting said beam towards a target electrode which is resonant at the oscillation fre-

quency to be generated and means for deflecting said beam over a surface which serves to intercept the beam intermittently before it strikes said target electrode, said target being of predetermined length and bent back upon itself to be substantially non-radiating.

4. In an oscillation generator, an electron discharge device having an electron gun, horizontal and vertical beam deflecting electrodes 10 effective when suitably energized to produce rotary beam deflection, an electrode having a plurality of apertures concentrically spaced so as to alternately intercept and pass electrons therethrough in accordance with said rotary beam deflection, an electron collector electrode, said electrodes being arranged in the order named, said collector electrode being so constructed and mounted that it, together with its mounting, forms a resonant circuit tuned to the frequency of oscillations generated by the intermittent transit of electrons through said apertures, and means for rendering said collector electrode substantially non-radiating, thereby to give it a relatively high impedance value.

5. In an oscillation generator, an electron discharge device having an electron gun, horizontal and vertical beam deflecting electrodes, an electrode having a plurality of apertures concentrically spaced so as to alternately intercept and pass electrons therethrough, and a resonant electron collector electrode, said electrodes being arranged in the order named, said collector electrode having an overall length equal to an even multiple of one-quarter wavelength, said collector being folded back upon itself to render the same substantially non-radiant.

6. In an oscillation generator, an electron discharge device having an electron gun, horizontal and vertical beam deflecting electrodes, an electrode having a plurality of apertures concentrically spaced so as to alternately intercept and pass electrons therethrough, an electron collector electrode, said electrodes being disposed in the order named, said collector electrode constituting at least a portion of a resonant circuit and forming an extension of the inner conductor of a coaxial conductor system, and means constituted by a portion of said outer conductor whereby said collector is surrounded and rendered substantially non-radiant.

7. In a cathode ray device, means for producing a focussed electron beam, means for rotatively deflecting said beam, means in the rotary path of said beam for intercepting the same at evenly spaced positions, an electron collector electrode positioned to receive a portion of said beam which is not intercepted, a sheath around said collector, said collector having such length that it together with said sheath forms a resonant and non-radiant system.

8. In a cathode ray device, means including an electron gun and a magnetic beam focussing device for producing a guided beam, a coaxial conductor system, a target electrode within the outer conductor of said coaxial system, and a connection from said target electrode to the inner conductor of said coaxial system, said connection being one-quarter of a wavelength long, whereby said target is a point of high impedance for electrons of said beam which impinge thereon.

9. Apparatus of the class described comprising a cathode ray tube having an electron gun, beam deflecting electrodes, an orificed electrode portions of which are so disposed as to intermittently intercept the electron beam when the

latter is deflected over a rotary path, a target electrode having a terminal support of predetermined electrical length, means for rendering said target electrode substantially non-radiating, and means for focussing electrons on said target electrode after they traverse the orifices of the orificed electrode, said target electrode together with its support, forming within the envelope of

said tube a resonant circuit whose frequency characteristic is tuned to the periodicity at which said beam traverses the series of orifices in said orificed electrode, said target electrode and its support possessing an impedance value which substantially matches that of a load connected thereto externally of said tube.
